When the wheel randomly stops at any one of the 12 zodiac animal symbols or 13 playing card characters the player(s) that bet on that particular zodiac animal symbol or playing card character will be rewarded 23 chips for every one chip bet. Unless the player bets on one of the SPLIT intersections which consists of any two zodiac animal symbols, two playing card characters, or one zodiac animal symbol and one playing card character,

the reward for the SPLIT intersection is 11 chips for every one chip bet. For example, a player bets one chip on Tiger and one chip on Horse. After the wheel stops spinning and the pointer points to Tiger, then the player will be rewarded 23 chips for the one chip bet on Tiger. A player can bet on as many zodiac animal symbols or playing card characters as desired. For the SPLIT intersection, assuming that a player bets one chip on Rat and Dragon. When the wheel stops spinning and it points to either Rat or Dragon, then the player will be rewarded 11 chips for the one chip bet. 5
